UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE SWITCHING APPARATUS.

Application filed November 11, 1919. Serial No. 337,243.

To all whom it may concern:

Be it known that I, LIPA POLINKOWSKY, a citizen of Russia, residing at Antwerp, Belgium, have invented certain new and useful Improvements in Telephone Switching Apparatus, of which the following is a full, clear, concise, and exact description.

This invention relates to telephone exchange systems and particularly to systems involving machine switching apparatus for setting up connections.

The object of the invention is to provide the selective switches employed in systems of this character with improved means for testing and seizing connecting circuits.

A feature of the invention is the provision, in automatic selective switches for extending connections to connecting circuits, of a plurality of test terminals for each circuit to which said switches have access so arranged in cooperative relation as to permit of the seizure of idle circuits and to guard such circuits when busy.

A further feature relates to the arrangement of the test terminals of each connecting circuit in such a manner in the terminal bank that the test brush of the selective switch in moving to such circuit first encounters an advance test terminal which determines the busy or idle condition of the circuit, and later by engaging a second terminal causes the arresting of the switch and the seizure of the desired circuit.

A still further feature relates to an arrangement in which one of a plurality of test terminals of a connecting circuit, being positioned in advance of the line terminals and engaged by the test brush prior to the engagement of the line terminals, permits the advance of said selector to the terminals of said circuit, if idle, and prevents the similar advance of other selectors to the terminals of such circuit while busy.

Such other and further features as are contemplated by the present invention will become more apparent from the following description and the appended claims.

In the drawings, there is shown to the left of the broken line in Fig. 1 the position of a wire chief or testing operator in the central exchange, together with the outgoing end of a test trunk leading to a group selecting switch in a distant exchange or satellite.

At the right of the broken line is shown the detailed circuits of the group selector in the 55 distant exchange in which the test trunk terminates.

Fig. 2 shows a final testing switch for use by the wire chief in making routine tests of subscribers' lines.

Fig. 3 illustrates a register controlling equipment located at the distant exchange, together with the switches shown in Figs. 1 and 2, and arranged to be positioned from the wire chief's desk for the purpose of 65 controlling the selective operations of said switches.

Briefly stated, the system in which this invention is embodied is one employed for performing routine tests of subscribers' 70 lines so designed that the wire chief at the central exchange is enabled to control the operation of selective switches used for testing purposes in a distant exchange to select a desired group of subscribers' lines. Having selected the required group of lines any line in such group may be chosen and the usual routine testing operations performed from the wire chief's desk. Inasmuch as the group selectors and final testing switches are 80 not in continual use for making such routine tests, it is only necessary that a limited number of these switches be provided. Accordingly, there may be one final testing switch for each group of subscribers' lines.

Since only one final testing switch is provided for each group of lines, an entire level in the group selector, through which these final switches are obtained, may be assigned to the connecting circuit leading to each of 90 the final switches. That is to say, in each level of the group selector shown in Fig. 1, there appears the terminals of a single connecting circuit leading to a final testing switch. While, as above mentioned, only one final switch is provided for each group of lines, it is obvious that two or more switches might be assigned to each group, in which case the terminals of as many switches as were assigned to a group of 100 lines, would appear in a single level of the group selector. As will be more clearly understood hereinafter the present invention, which relates to a novel testing arrangement in selector switches, is particularly applicable to systems of this character, wherein it

is possible to devote an entire level in the selector bank to a comparatively few connecting circuits.

It is believed that a more thorough understanding of the invention is to be had from a detailed description of the operation of the system in which the same is embodied.

Assume that the wire chief in the central exchange wishes to make a routine test of a group of subscribers' lines in a distant exchange, to which group, for example, the line 400 belongs. He first inserts the plug 200 of his equipment into the jack 201 of trunk 211—212 leading to a first group selector 5 which has access to the proper final testing switch. When plug 200 is inserted in jack 201, a circuit is closed from battery over the sleeve of the plug and jack, through the winding of relay 202 to ground. Relay 202 10 closes a circuit for guard lamp 203 to indicate that this trunk circuit is busy. A circuit is also closed for relay 222 traceable from battery through the winding of said relay, contact 223 (1), conductor 211, ring of jack 15 201 and plug 200, through the wire chief's apparatus, tip of jack 200 and plug 201, conductor 212, contact 239 (1) to ground. Relay 222 energizes and closes the following circuit: ground, armature and front contact 25 of relay 222, contact 238 (1), through the right-hand winding of relay 234, contact 246 (1), conductor 293, contact 368 (1) of sequence switch 350, contact 322 (1) of sequence switch 320, through the left-hand 30 winding of relay 323 to battery and ground.

It may be noted at this point that all sequence switch contacts to the left of the vertical broken line of Fig. 3, are controlled by sequence switch 320, and all contacts to the 40 right of said line are controlled by sequence switch 350.

Relay 234 energizes in the above traced circuit and closes a circuit through its left-hand low resistance winding, and the winding 45 of relay 232 to ground, in parallel with that established through its right-hand winding. Relay 232, thereupon energizes and closes a circuit from battery through the winding of relay 237, contact 236 (1) to 50 ground, at the front contact and armature of relay 232. Relay 237 at its front contact completes a circuit for the left-hand winding of relay 257. Relay 257 in turn closes a circuit from ground over its armature and contact, contact 240 (1), through the winding of 55 sequence switch 220 to battery and ground. Sequence switch 220 moves out of position 1 and into position 3. When sequence switch 220 reaches position 2, a circuit is closed 60 from battery through resistance 261, contact 228 (2 to 12), winding of relay 231, contact and right-hand armature of relay 202, armature and contact of relay 204, resistance 205, conductor 214, to ground. Relay 231 energizes and opens the circuit for relay 273

which would otherwise be closed when sequence switch 220 reaches position 3. Relay 231 and relays 237 and 257 are for the purpose of controlling release, as will be described hereinafter.

In position 3 of sequence switch 220, the register controlling mechanism shown in Fig. 3, is associated with the trunk 211—212 by the closure of contacts 242 and 243. The wire chief by depressing key 215 closes an impulse circuit from his sender 216 through to the stepping relay 325 at the register mechanism. This impulse circuit may be traced from battery, through the left-hand winding of stepping relay 325, conductor 70 217, contact 242 (3), contact 211, ring of jack 201, ring of plug 200, through the lower contact of key 215, sender 216, upper contact of key 215, tip of plug 200, tip of jack 201, conductor 212, contact 243 (3), conductor 75 218, contact and left-hand armature of relay 339, through the right-hand winding of relay 325 to ground. Relay 325 energizes in this circuit.

At the time the above traced circuit was 80 closed for relay 234 in series with the left-hand winding of relay 323, this latter relay also became energized. The sequence switch 320 is therefore driven from position 1 into position 3, by means of a circuit from battery through the winding of said sequence switch, right-hand winding of relay 323, front contact and armature of relay 323 to ground. When the master contact 321 of sequence switch 320 closes on leaving position 90 100 95

1, the right-hand winding of relay 323 is shunted, and when contact 322 opens the circuit through the left-hand winding of relay 323 is broken, thereby causing the deenergization of said relay. When sequence switch 105 320 reaches position 3 and relay 323 releases its armature, a circuit is closed from battery through contact 327 (3), winding of relay 326, back contact and armature of relay 323 to ground. Relay 326 closes a circuit from 110 ground at the armature and front contact of stepping relay 325, through the armature and front contact of relay 326, contact 330 (3) right-hand winding and contact and armature of relay 329, contact 328 (3), 115 through the winding of the thousands register 110, to battery and ground. In parallel to this circuit a circuit is also closed at the same time for the left-hand winding of relay 329. Relay 329 being differential 120 does not attract its armature when both of these windings energize. The thousands register 110, however, energizes and moves out of position 0. When the master contact 111 of the thousands register closes between 125 position 0 and position 1, the right-hand winding of differential relay 329 is shunted and said relay attracts its armature. Under the control of its master contact, the register 110 advances into position 1.

At the time sequence switch 320 reaches position 3, the primary winding of the dialing tone coil 324 is closed in series with the interrupter 333 at contact 332. The wire chief, hearing the characteristic tone in the usual manner, understands that he may proceed to transmit impulses to the register controlling mechanism. In operating his sender 216 for the first series of impulses, 10 the first interruption of the impulse circuit causes the deenergization of stepping relay 325. The left-hand winding of differential relay 329 is thereupon opened and this relay releases. At the following closure of the impulse circuit, the above traced circuit is 15 closed for the register 110 in series with right-hand winding of relay 329. Register 110 thereupon moves from position 1 into position 2, and relay 329 energizes in the 20 manner described. On the second interruption of the line, relay 329 deenergizes, and at the second closure of the line register 110 is driven forward another position. This 25 procedure continues, the register 110 advancing one position for each impulse sent from the wire chief's sender. The sender 216 is so designed that the last interruption of the line for each impulse series is comparatively longer than the preceding interruptions. At 30 this last comparatively long interruption the circuit from battery, through the windings of relay 334, contact 342 (3), back contact and armature of relay 325 to ground is maintained closed for a period sufficient to 35 permit the relay 334 to attract its armature. This relay, being slow to energize, did not operate on each of the preceding short interruptions of the line. Relay 334 closes a circuit from ground, armature and contact 40 of said relay, through the right-hand winding of relay 323, winding of sequence switch 320 to battery and ground to drive sequence switch 320 out of position 3 and into position 6. In leaving position 3 the master contact 321 short-circuits the right-hand winding of relay 323 and the circuit of relay 334 being opened at contact 342, relay 323 de- 45 energizes before sequence switch 320 reaches position 6.

On coming into position 6 sequence switch 50 320 shifts the control of the stepping relay from the thousands register 110 to the hundreds register 120, and a circuit is closed from ground, armature and front contact of relay 325, armature and front contact of relay 326, contact 115 of register 110, right-hand winding and contact of armature of relay 329, contact 328 (6), winding of register 120 to battery and ground. The circuit just traced leads through the contact 115 55 of the thousands register 110, either closed in position 9 or position 0, as will be more fully explained hereinafter. The register 120 energizing in this circuit moves from position 0 into position 1, in the manner de-

scribed in connection with the thousands register 110. At each interruption of the impulse circuit for the second series of impulses, the register 120 is advanced through one position. At the last interruption of the 70 impulse circuit slow-to-energize relay 334, attracts its armature and closes a circuit as above described to drive sequence switch 320 out of position 6 and into position 10.

When the line circuit again closes, a circuit 75 is completed from ground, armature and front contact of relay 325, armature and front contact of relay 326, contact 115, right-hand winding and contact and armature of relay 329, contact 335 (10), winding of tens 80 register 130 to battery and ground. The tens register 130 is moved through one position for each impulse sent in the tens series. At the end of this series, relay 334 energizes 85 and completes a circuit for driving sequence switch 320 out of position 10 and into position 13. A circuit is now closed from ground, armature and front contact of relay 325, armature and front contact of relay 326, contact 115, right-hand winding and contact 90 and armature of relay 329, contact 335 (13), winding of a units register 140 to battery and ground. When the units register 140 has been positioned in accordance with the 95 number of impulses in the final series, relay 334 is again energized and sequence switch 320 is driven from position 13 into position 16.

Before proceeding further with the description of the operation, a brief explanation 100 will be given of the type of register controlling mechanism used in this system. The registering controlling mechanism comprises a plurality of sequence switch registers having 10 controlling positions, one for 105 each digit. Upon being positioned, these registers are driven under the control of the impulse sender from position 0 to a position corresponding to the number of impulses sent. Having been set in these positions, 110 they are then driven through their remaining positions to position 0 for controlling the selective movements on the switches. It will be seen that the number of positions 115 through which each of the registers are moved during their return to normal is the complement of the number of impulses sent from the impulse sender in setting the registers. It therefore becomes necessary to design the senders so that each impulse series sent contains a number of impulses 120 equal to the complement of the actual digit concerned. In the present system the distant exchange in which the controlling mechanism shown in Fig. 3 is located is assumed to have a capacity of 2,000 lines. Consequently the thousands register 110 will always be set in one or the other of its two 125 controlling positions 9 and 0. That is to say, if the desired line is in the even or zero 130

thousand, register 110 will be adjusted to position 0, whereas if the called line belongs to the odd thousand, register 110 will be set in position 9, the complement of the digit 1.

When the first two registers 110 and 120 have been positioned, which corresponds to sequence switch 320 moving from position 6 to position 10, thousands and hundreds

- 10 selection takes place without waiting for the remaining registers to be set. In position 7 of sequence switch 320 a circuit is completed from ground, contact 338, contact 113 of register 110, contact 352 (1), winding of sequence switch 350 to battery and ground. Sequence switch 350 moves out of position 1 and into position 3. In this position the fundamental circuit is established preparatory to controlling the brush tripping operation at the group selector. This circuit may be traced from battery through the winding of relay 222, contact 247 (3), conductor 296, winding of stepping relay 355, armature and contact of relay 357, to ground, at contact 256 (3). Relay 222 energizes and closes a circuit from ground over its armature and front contact, contact 227 (3), winding of sequence switch 220 to battery to drive said sequence switch out of position 3 into position 4. In position 4 of sequence switch 220, the brush tripping power magnet 248 is energized in a circuit from battery through the winding thereof, contact 249 (4) to ground, at the front contact and armature 35 of relay 222. The brush tripping spindle is thereby rotated to select the particular one of a plurality of sets of brushes that has access to the desired level of terminals in the selector bank. As each brush tripping position is passed by the tripping spindle, the interrupter contact 250 closes a circuit for relay 222 including contact 223 (4) in shunt of the stepping relay 355 in the fundamental circuit. At the first closure of the contact 250, relay 355 deenergizes and the following circuit is completed; ground, contact 369 (3), armature and contact of relay 355, left-hand winding and contact and armature of relay 359, contact 361 (3), contact 122, winding of the hundreds register 120 to battery and ground. In parallel to this circuit, a circuit is also closed through the right-hand winding of relay 359. Relay 359 is made differential and therefore does not attract its armature when both of its windings are energized. The hundreds register 120, however, energizes and moves from the position to which it was adjusted to the next succeeding position. In 60 the same manner as described in connection with the operation of the differential relay 329, the relay 359 is permitted to energize when the master contact of the register is closed in passing from one position to another. As the brush tripping spindle reaches

its first tripping position, contact 250 is opened. The stepping relay 359 energizes to permit the deenergization of the differential relay 359. This operation proceeds until the hundreds register reaches position 0. As soon after register 120 reaches position 0, as the interrupter contact 250 again closes, and relay 355 deenergizes, a circuit is closed from battery through the winding of sequence switch 350, contact 363 (3), contact 114 (assuming register 110 to be standing in position 0, contact 343 (3), contact 124 (0), contact 361 (3), armature and contact of left-hand winding of relay 359, contact and armature of relay 359, to ground, at contact 369. In parallel to this circuit a circuit is also completed for the energization of relay 357. The relay 357 opens the fundamental circuit to guard against further operation of the tripping spindle, and sequence switch 350 energizes and moves into position 4. When the tripping spindle interrupter contact 250 again opens, relay 222 deenergizes, since the fundamental circuit is now broken at the register controlling mechanism. Relay 222 closes a circuit from ground over its armature and back contact, contact 229 (4), winding of sequence switch 220 to battery and ground to drive such sequence switch into position 5.

The selected set of brushes, as for example, the brushes 251, 252 and 253, are now ready to be driven over the terminal level containing the terminals 475, 476, 488 and 489 of the connecting circuit leading to the proper final selector. The connecting circuit leading to the final selector switch is provided in the terminal bank of the group selector, with the two line terminals 475 and 476, and also with two terminals 488 and 489 in the test row. The terminal 488 is so arranged in the level that the test brush 252 engages the same, before the line brushes 251 and 253 have reached terminals 475 and 476. The terminal 489 is so arranged that the test brush 252 makes engagement therewith simultaneously with the engagement of brushes 251 and 253 with terminals 475 and 476. If the final testing switch is idle, the test brush 252 of the group selector passes over terminal 488 and comes to rest of terminal 489, permitting the seizure of the connecting circuit leading to said final switch. If, however, the final switch is busy at the time test brush 252 reaches terminal 488, a busy condition on this terminal will cause the group selector to stop before its brushes have reached terminals 475, 476 and 489.

The testing operation of the group selector is effected by means of a circuit from battery through the winding of brush carriage power magnet 241, contact 254 (5), to ground at the contact and armature of relay 232. The brush carriage rotates and advances the

test brush 252 first into engagement with terminal 480. A circuit is then completed from battery over terminal 480, brush 252, contact 246, (5), right-hand winding of relay 234 to ground at contact 239. Relay 234 energizes and closes a circuit through its left-hand winding, and the winding of relay 232 to ground at the contact 239. Relay 232 attracts its armature and opens the circuit of power magnet 241 causing the brush carriage to come to rest. Relay 232 also closes a circuit including contact 229 (5) for driving sequence switch 220 out of position 5 and into position 11. On leaving position 5, sequence switch contact 246 is opened and relays 234 and 232 are deenergized. Relay 232 again closes the circuit of the power magnet 241, and the brush carriage resumes its rotation. The speed of the brush carriage is so adjusted with respect to the speed of sequence switch 220, that the test brush 252 reaches the terminal 488 prior to the arrival of sequence switch 220 in position 11. Assuming the final test switch 25 to be idle, no busy condition will be found on the test terminal 488 by the brush 252, and sequence switch 220 will come to rest in position 11. The brush carriage, therefore, continues to rotate by means of the circuit 30 traced and the brushes 251, 253 and 252 are advanced into engagement respectively with terminals 475, 476 and 489.

Upon test brush 252 making contact with terminal 489, a circuit is established from battery, through resistance 442, contact 441 (1) of sequence switch 450, terminal 489, brush 252, contact 246 (11), right-hand winding of relay 234 to ground, at contact 239. Relay 234 energizes and closes a parallel circuit through its left-hand winding and the winding of relay 232 to ground at contact 239. Relay 232 energizing, opens the power circuit of magnet 231 and closes a circuit from battery, through the winding 40 of holding magnet 245 to ground at the front contact and armature of relay 232. Holding magnet 245 operates to arrest the brush carriage with the brushes accurately centered upon the terminals 475, 476 and 489. Relay 232 also closes a circuit from ground over its armature and front contact, contact 229 (11), winding of sequence switch 220 to battery and ground. Sequence switch 220 advances from position 11 into position 12. With sequence switch 220 in position 12, relay 222 is maintained energized in a circuit including contact 247 (12), conductor 293, contact 368 (1 to 9) back contact and right-hand armature of relay 60 339 to ground at contact 340. The closure of sequence switch contacts 255 and 256 in position 12 now extends the fundamental circuit from the register controlling mechanism through to the final testing switch. This 65 circuit may be traced from battery through

the winding of relay 452, contact 444 (1), contact 476, brush 253, contact 256 (12), conductor 296, winding of stepping relay 355, armature and contact of relay 357, contact 356 (5), conductor 297, contact 255 75 (12), brush 251, terminal 475 to ground, at contact 445. It will be noted that the sequence switch 350 advances from position 4 into position 5 to close the fundamental circuit at contact 356, as soon as the units 75 register has been positioned. The circuit for moving sequence switch 350 into position 5 may be traced from battery, through the winding of said sequence switch contact 363 (4) to ground at contact 341 (16). 80

The relay 452 energizes and completes a circuit from ground, contact 466 (1), armature and front contact of relay 452, contact 446 (1), through the winding of sequence switch 450 to battery and ground, moving 85 sequence switch 450 out of position 1 and into position 2. In position 2, sequence switch 450 closes a circuit from battery through the windings of relays 484 and 483, contact 443 (2), terminal 489, test brush 252, contact 246 (12), right-hand winding of relay 234 to ground at contact 239 (12). Relay 234 energizes and closes through its left-hand winding and the winding of relay 232, a circuit in parallel with the one just traced. 90

Relay 484 energizes and prevents sequence switch 450 from moving out of position 2 by means of a circuit which would otherwise be closed over contact 467 (2). The brush tripping spindle is now rotated to select the 100 proper set of brushes as determined by the position of the tens register 130. The circuit for the tripping spindle magnet 448 may be traced from battery through the winding of said magnet, contact 447 (2), front contact and armature of relay 452 to ground of contact 466. For each brush tripping position passed over a circuit is closed for relay 452, over contact 449 (2), and interrupter brush 455 in shunt of the stepping relay 355 105 110 in the fundamental circuit. The first shunting of relay 355 causes this relay to deenergize and close the following circuit; ground, contact 369 (5), armature and contact of relay 355, left-hand winding and contact and armature of relay 359, contact 367 (5), contact 132, winding of tens register 130 to battery and ground. Register 130 advances in the manner described from the position to which it was adjusted, into the next succeeding position. At each of the following closures of the interrupter 455, the stepping relay 355 is deenergized and the tens register 130 moves forward until it reaches 0. At the next closure of interrupter 455 following the arrival of register 130 in position 0, the following circuit is closed for sequence switch 350 to bring about the change over operation: from battery, through the winding of said sequence switch, contact 352 (5), 130

contact 134 (0), contact 367 (5), armature and contact and left-hand winding of relay 359, contact and armature of relay 355 to ground at contact 369 (5). In parallel to this circuit a circuit is also closed for relay 357. The relay 357 maintains the fundamental circuit open while sequence switch 320 energizes and advances from position 5 into position 7. As soon as the interrupter 10 455 again opens after the fundamental circuit has been severed at the register controlling mechanism, the relay 452 deenergizes. A circuit is then closed from battery through the winding of sequence switch 450, contact 15 446 (2), back contact and armature of relay 452 to ground at contact 466 (2), sequence switch 450 advances from position 2, into position 3.

As soon as contact 367 is opened, as sequence switch 350 moves out of position 5, relay 357 deenergizes and closes the fundamental circuit at the register controlling mechanism. Relays 452 and 355 therefore immediately become energized. The operation of relay 452 closes a circuit from battery through the winding of sequence switch 20 450, contact 446 (3), front contact and armature of relay 452 to ground at contact 466 (3). Sequence switch 450 moves out of position 25 3 and into position 4. In this position the brush carriage of the final testing switch carrying brushes 410, 411 and 412 is rotated by means of the power magnet 461. The circuit of magnet 461 may be traced from battery, through the winding thereof, contact 30 456 (4), front contact and armature of relay 452 to ground at contact 466 (4) as the brushes approach the first set of terminals in the level the interrupter contact 457 closes 35 a circuit for relay 452 including contact 449 (4), in shunt of the stepping relay 355 in the fundamental circuit. The deenergization of relay 355 causes a circuit to be closed from ground, over contact 369 (7), armature and contact of relay 355, left-hand winding and contact and armature of relay 359, contact 40 367 (7), contact 142, winding of the units register 140 to battery and ground. The units register 140 advances through one position in the well-known manner. When the units register 140 later reaches position 0, the brushes 410, 411 and 412 are about to make engagement with terminals of the desired subscriber's line 400. At this time the 45 interrupter contact 457 is closed and relay 355 is deenergized. Hence a circuit is established from battery through the winding of sequence switch 350, contact 352 (7), contact 144 to 0, back contact and armature of relay 374, contact 143 (0), contact 367 (7), armature and contact and left-hand winding of relay 359, contact and armature of relay 355 to ground of contact 369 (7). A parallel 50 circuit is also for the relay 357 which operates to hold the fundamental circuit open. 60 65

The sequence switch 350 energizes and advances from position 7 into position 18. On reaching position 18, the sequence switch 350 is immediately advanced into its normal position 1, by means of a circuit from battery 70 through the winding of said sequence switch contact 352 (18), back contact and armature of relay 326, contact 336 (18) to ground. When the brushes 410, 411 and 412 are accurately centered on the terminal of the desired line the interrupter contact 457 opens and relay 452 deenergizes. A circuit is thereupon closed from battery through the winding of sequence switch 450, contact 446 (4), back contact and armatures of relay 452 75 to ground at contact 466 (4). Sequence switch 450 moves out of position 4 and into position 9.

The sequence switch 350 on leaving position 9 opens at its contact 368 the circuit 80 which up to this time has been maintaining the energization of relay 222. The relay 222 by deenergizing closes a circuit from ground over its armature and back contact and contact 229 (12) for driving sequence switch 90 220 into position 14. In leaving position 12, sequence switch contacts 242 and 243 open the circuit of the stepping relay 325. This relay deenergizes and causes the restoration of the register controlling mechanism. The 95 deenergization of relay 325 closes a circuit from ground over its armature and back contact, contact 348 (16) winding of sequence switch 320 to battery and ground. Sequence switch 320 advances into position 17. In 100 this position, relay 323 is energized by means of a circuit from battery, through the left-hand winding of relay 323, contact 322 (17) to ground at contact 369 (1). Relay 323 closes a circuit from ground through its 105 armature and front contact and right-hand winding, and the winding of sequence switch 320 to battery and ground. Sequence switch 320 moves out of position 17 and into position 1. The master contact 321 of sequence 110 switch 320 shunts the winding of relay 323, so that this relay is permitted to deenergize upon the opening of contact 322. The register mechanism is now completely restored to its normal position.

When sequence switch 220 leaves position 12, the circuit of relay 231 is opened at contact 228 (12). In position 13, this relay is maintained energized by means of a secondary circuit from battery through resistance 262, and contact 226 (13). As sequence switch 214 leaves position 12, the hereinto fore traced circuit for relays 484 and 483 in series with relays 234 and 232, was opened at contact 246 (12). Relays 234 and 232 de- 120 energized, but relays 484 and 483 are maintained energized in the following circuit in position 14 of sequence switch 220: battery through the windings of relays 484 and 483, contact 443 (10), terminal 489, brush 252, 125 130

contact 228 (14), winding of relay 231, conductor 213, contact and right-hand armature of relay 202, armature and contact of relay 204, resistance 205, conductor 214 to ground. 5 The relays 231 and 484 being sensitive energize in this circuit, whereas the relay 483 being marginal, will not operate in series with the resistance 205. The test trunk 211, 212 leading from the wire chief's desk is 10 now connected directly through to the connecting circuit of the test switch in Fig. 2, over sequence switch contacts 255 and 256 closed in position 14. The relay 452 again energizes in series with the trunk 211 and 15 212 and closes a circuit from ground over contact 466 (9), armature and front contact of relay 452, contact 446 (9), winding of sequence switch 450 to battery and ground to drive sequence switch 450 into position 10. 20 The apparatus remains in this condition until the wire chief is ready to proceed with the testing of the selected line. When he releases key 215 for this purpose, the relay 452 deenergizes and a circuit is established 25 from ground over contact 466 (10), armature and back contact of relay 452, contact 446, (10), winding of sequence switch 450 to battery and ground. Sequence switch 450 moves out of position 10 and into position 30 11 in which position the testing circuit is extended to the brushes 410 and 411 by the closure of contact 445 and 444. After having performed the necessary test of the line 400, the wire chief may desire to test other lines in this group in the same manner. For this purpose a provision is made whereby he may advance the final testing switch step-by-step into engagement with the successive lines to the group without the necessity of 35 resetting the register controlling mechanism to select the next succeeding line in the group. For example, he depresses a key 208, individual to the test trunk 211-212, and also a common key 207. The closure of these 40 keys complete a circuit for relays 204 and 209. The relay 204 immediately energizes and opens the circuit of relays 231 and 484 which thereupon release their armatures. The deenergization of relay 484 results in 45 the closure of a circuit from battery through the winding of relay 486, left-hand winding of relay 485, contact 467 (11), back contact and armature of relay 484 to ground. Relay 485 energizes and locks up over its right-hand winding in series with the winding of 50 relay 452. Relay 209 is made slow to operate so that it does not close its contacts until a predetermined interval after the operation of relay 204. When relay 209 attracts its 55 armature relay 204 is shunted out and deenergizes to again close the circuit of relays 231 and 484. Relay 484 now completes a circuit from ground over its armature and front contact, armature and front contact 60 of relay 452, contact 466 (11), winding of 65 sequence switch 450 to battery and ground. Sequence switch 450 moves into position 12, where a circuit is completed for the brush carriage power magnet 461. This circuit leads from battery through the winding of 70 said magnet, contact 456 (12), front contact and armature of relay 452 to ground, at the front contact and armature of relay 484. The brush carriage rotates and upon the closure of contact 457, a substitute circuit is 75 closed for relay 452, over sequence switch contact 449 (12) in shunt of the circuit through the right-hand winding of relay 485. Relay 485 therefore deenergizes and opens 80 the original energizing circuit of relay 452, so that this relay deenergizes as soon as the brushes 410, 411 and 412 reach the next set of line terminals and interrupter contact 457 opens. The deenergization of relay 452 opens the circuit of the power magnet 461 85 causing the brush carriage to come to rest. The deenergization of relay 452 also closes a circuit 452 to the winding of holding magnet 465, contact 455 (12), contact and armature 481, back contact and armature of relay 90 452 to ground at the front contact of armature 484. The holding magnet serves in a well-known manner to bring the brushes accurately in engagement with the line terminals. In parallel of the circuit of the holding magnet 465, a circuit is also closed for 95 relay 482, over sequence switch contact 458 (12). Relay 482, which is slow to energize, attracts its armature and closes a circuit for a second slow-to-energize relay 481. When 100 relay 481 becomes energized it opens the circuit of the holding magnet 465. After this line has been tested by the wire chief, the final testing switch may be advanced to the terminals of the next succeeding line in the 105 manner already described. Each time the relay 484 releases its armature, it closes, as above noted, a circuit for relay 486. Relay 486 in turn completes a circuit for relay 487. This latter relay when energized, closes a circuit 110 for restoring the sequence switch 450. Relays 486 and 487, however, are made slow to energize and do not have sufficient time to operate, while relay 484 is deenergized during the operation of the final testing switch 115 from one set of terminals to another. In a similar manner, the relay 231 closes a circuit for relay 237 which in turn closes a circuit for relay 257. Relay 257 by energizing, 120 completes a circuit from ground over its armature and back contact 240 (14), through its left-hand winding and the winding of sequence switch 220 to battery. This circuit results in driving the sequence switch 220 into position 17. The relays 257 and 237, 125 being made slow to operate, will not have time to close in succession during the brief intervals that relay 231 is deenergized in the operation of advancing the final testing switch from one set of terminals to the next. 130

If the wire chief has completed the testing of the subscriber's lines, and wishes to release the apparatus, he removes the plug 200 from the test jack 201. The relay 202 therefore releases its armature and permanently opens the circuit of relays 231 and 484. Relay 231 causes the successive energization of relays 237 and 257, and sequence switch 220 is driven into position 17 as above explained. In position 17 of sequence switch 220, the brush carriage of the group selector is restored to normal position by means of a circuit from battery through the winding of power magnet 241, contact 254 (17), back contact and armature and relay 232 to ground. On reaching its normal position the brush 221 closes a circuit from battery through the resistance 262, contact 226 (17), brush 221, winding of relay 232 to ground at contact 239 (17). Relay 232 attracts its armature and closes a circuit from battery through the winding of sequence switch 220, contact 229 (17 to 18), front contact and armature of relay 232 to ground. Sequence switch 220 thereupon moves into position 1. The permanent deenergization of relay 484 permits slow-to-energize relays 486 and 487 to attract their armatures as above described. Relay 487 closes the circuit for driving sequence switch 420 out of position 12 and into position 17. On leaving position 12 the circuit of relay 486 is opened at contact 467, relay 486 immediately deenergizes and causes the deenergization of relay 487 so that sequence switch 450 comes to rest when it reaches position 17. The brush carriage of the final selector is now restored to normal position by means of a circuit from battery through the winding of power magnet 461, contact 456 (17), back contact and armature of relay 452 to ground at contact 466 (17). On reaching its normal position the interrupter brush 457 closes a circuit from battery through the winding of sequence switch 450, contact 446 (17), front contact and armatures of relay 452 to ground at contact 466 (17). Sequence switch 450 thereupon moves out of position 17 and into its normal position 1.

Assume now that the final test switch shown in Fig. 2 is already engaged by some other group selector at the time the selector shown, attempts to make connection therewith. In this case the sequence switch 450 will be in some position other than position 1, and battery will be supplied to the test terminal 488 over contact 441 (2 to 18). Therefore upon the test brush 252 engaging in the terminal 488, the following circuit is closed: battery through resistance 442, contact 441 (2 to 18), terminal 488, brush 252, contact 246, through the right-hand winding of relay 234 to ground at contact 239. It will be noted that while the sequence switch 220 does not reach position 11 until after

the test brush 252 has made engagement with the test terminal 488, said sequence switch will have reached position 8 by the time the test brush engages terminal 488. Therefore the contact 246 will have been closed by the time the terminal 488 is reached, and relay 234 energizes in the circuit above traced. Relay 234 closes a circuit through its left-hand winding, and the winding of relay 232 in parallel to the circuit traced through the right-hand winding of relay 234. Relay 232 energizes and closes a circuit from battery through the winding of relay 224, contact 244 (7 to 10), front contact and armature of relay 232 to ground. Relay 224 attracts its armature and locks up over a circuit including the back contact and armature of relay 237. Sequence switch 220, instead of now stopping in position 11 to permit the advance of the group selector to the terminals 475, 476 and 489, continues to move over positions 12 and 14, and comes to rest in position 16. The circuit from driving sequence switch 220 in position 16 may be traced from battery through the winding of said sequence switch contact 227 (7 to 14), contact and left-hand armature of relay 224 to ground. A busy condition encountered on the test terminal 488 thus serves to arrest the brush carriage of the group selector before the same can advance into engagement with the terminals of the connecting circuit leading to the final test switch. In position 16 of the sequence switch 220, a busy tone from the machine 266 is transmitted in the well-known manner to the wire chief's apparatus due to the closure of contacts 242 and 243. The wire chief hearing this busy tone knows that the final test switch is engaged and removes the plug 200 from jack 201. Release of the group selector now takes place in a manner similar to that previously described.

What is claimed is:

1. In a telephone system, a connecting circuit, a selective switch for extending telephone connections over said circuit, a plurality of terminals individual to said circuit in said switch, a brush for said switch, means for moving said brush successively into engagement with said terminals, and means rendered effective by the engagement of said brush with said terminals for testing and seizing the connecting circuit.
2. In a telephone system, a connecting circuit, a selective switch for extending telephone connections over said circuit, a plurality of terminals individual to said circuit in said switch, a brush for said switch, means for moving said brush successively into engagement with said terminals, means rendered effective by the engagement of said brush with one of said terminals for testing the condition of the connecting circuit, and means responsive to the engagement of said

brush with another of said terminals for seizing said connecting circuit.

3. In a telephone system, a connecting circuit, a selective switch for extending telephone connections over said circuit, a pair of terminals individual to said circuit in said switch, a brush for said switch, means for moving said brush successively into engagement with said terminals, means rendered effective by the engagement of said brush with one of said terminals for testing the condition of the connecting circuit, and means responsive to the engagement of said brush with the second of said terminals for seizing the connecting circuit.

4. In a telephone system, a selective switch, a connecting circuit, a plurality of terminals individual to said circuit in said switch, a brush for said switch arranged to make contact with said terminals, means for driving said brush over one of said terminals to test the condition of the connecting circuit, and means operated upon the engagement of said brush with another of said terminals for stopping the selective switch to seize said connecting circuit.

5. In a telephone system, a selective switch, a connecting circuit, a plurality of terminals in said switch, a brush for said switch arranged to make contact with said terminals, means for driving said brush over one of said terminals to test the condition of the connecting circuit, means operated upon the engagement of said brush with another of said terminals for stopping the selective switch to seize said connecting circuit, and means for placing a busy condition on the first of said terminals.

40 6. In a telephone system, a selective switch, a connecting circuit appearing in said switch, means for driving said switch into engagement with said circuit, a plurality of terminals for said circuit, a brush for said switch arranged to engage successively said terminals, means effective upon the engagement of said brush with one of

said terminals for testing the condition of the connecting circuit, means responsive to the engagement of said brush with another 50 of said terminals for stopping the selective switch in engagement with the connecting circuit, and means for stopping said selective switch before it engages the connecting circuit if said connecting circuit is busy. 55

7. In a telephone system, a selective switch, a connecting circuit appearing in said switch, means for driving said switch into engagement with said circuit, a plurality of terminals for said circuit, a brush 60 for said switch arranged to engage successively said terminals, means effective upon the engagement of said brush with one of said terminals for testing the condition of the connecting circuit, means responsive to the engagement of said brush with another 65 of said terminals for stopping the selective switch in engagement with the connecting circuit, and means responsive to the engagement of said brush with the first of said terminals for stopping the selective switch before it engages the connecting circuit, if 70 said connecting circuit is busy.

8. In a telephone system, a selective switch, a connecting circuit appearing in 75 said switch, means for driving said switch into engagement with said circuit, a pair of terminals for said circuit, a brush for said switch arranged to engage successively said terminals, means effective upon the engagement of said brush with the first of said 80 terminals for testing the condition of the connecting circuit, means responsive to the engagement of said brush with the second of said terminals for stopping the selective 85 switch in engagement with the connecting circuit, and means for stopping said selective switch before it engages said second terminal, if said connecting circuit is busy.

In witness whereof, I hereunto subscribe 90 my name this 13th day of October, A. D. 1919.

LIPA POLINKOWSKY.
